UNITED STATES PATENT OFFICE.

BURT F. UPHAM, OF BOSTON, MASSACHUSETTS, ASSIGNOR TO SOUTHGATE MACHINERY CO., OF BOSTON, MASSACHUSETTS, A CORPORATION OF MASSACHUSETTS.

METHOD OF BENDING ELECTROTYPE-PLATES.

No. 909,832.

Specification of Letters Patent.

Patented Jan. 12, 1909.

Application filed December 17, 1906, Serial No. 348,313. Renewed September 30, 1908. Serial No. 455,398.

To all whom it may concern:

Be it known that I, BURT F. UPHAM, a citizen of the United States, and a resident of the city of Boston, in the county of Suffolk and Commonwealth of Massachusetts, have invented certain new and useful Improvements in Methods of Bending Electrotype-Plates, of which the following is a full, clear, and exact description.

10 In the process of bending electrotype plates for use upon cylinder presses, it has hitherto been customary to lay the electrotype shell face downward upon a flat surface; then back the same with melted alloy

15 to a thickness of substantially half an inch; then, after the alloy has well hardened, to plane it down until shell and all are brought to a total thickness of three-sixteenths of an inch; and, finally, to place the same face

20 downward within a concave mold of the desired curvature, and press the backed shell to conform therewith.

For certain kinds of work, as for presses employing both flat and curved printing surfaces, this method is highly objectionable, inasmuch as in the process of bending, the electrotype shell is appreciably elongated, to an extent amounting in the larger plates to fully an eighth of an inch.

30 The flat plate, used in conjunction with this curved one, not being thus elongated, the two will not match, and, hence, where one impression is designed to be superimposed upon the other, as in color work, very

35 imperfect results must follow.

I have found that it is not practical to place the electrotype shell in a concave mold corresponding in curvature to the cylinder upon which the electrotype is to be used, 40 and then to pour therein the melted backing-metal to the required final thickness, especially for large plates, on account of the failure of the molten metal to flow with uniformity to the extreme limits of the plate, 45 and to consequently form depressions and blow-holes whereby the plate is rendered worthless for withstanding the heavy pressures to which the printing surface is subjected. Neither is it practical, in the usual

50 printing establishment, to back up a properly curved electrotype shell to the custom-

ary excessive thickness, and then to plane down the backing to gage by some form of planing machine. A machine for thus planing a cylindrical concave surface would be 55 too complicated and expensive to be owned and operated by such establishments.

The object of my invention is the production of a process whereby electrotype plates may be made of the proper curvature without such undesirable elongation, and hence fit for use in conjunction with flat plates.

My process consists essentially in backing up the electrotype shell, or other printing surface, and then treating the same in accordance with a process certain steps of which include two bendings opposite in direction; the last bending being to a curvature disposed to fit the printing surface to the cylinder upon which it is to be used, and the process serving to eliminate superficial distortion of such surface. By this method, the contraction of the first bending acts to entirely neutralize the elongation of the second, and so produces a curved plate perfectly matching the original flat plate.

I have devised two methods for carrying this process into effect, the first consisting in backing up the electrotype shell in a concave mold; then bending it flat and planing 80 it to gage, and finally curving it in the customary manner.

My second method consists in backing up the electrotype shell in the usual manner upon a flat surface; then curving it face inward upon a cylindrical surface and routing or turning it to gage, and finally bending it back to a flat contour, and then curving it in the usual way.

Referring to the drawings forming part 90 of this specification, Figure 1 is a side elevation in diagram of the mold used in the first step of my first process. Fig. 2 illustrates the second step in said process. Fig. 3 shows the mold used in the third step of 95 said process. Fig. 4 illustrates the first step in my second process. Fig. 5 shows the second step in this second process, and Fig. 6 shows the final step therein.

In Fig. 1, 10 designates the concave 100 mold used in the first step of my first method; 1, the electrotype shell; 2, the lead

backing poured thereon to the half-inch thickness usually preferred, and 11 is the shaper for causing the upper surface of the lead to be concentric with the printing surface. From this mold, the plate is removed to a flat surface 12, upon which it is laid face-downward and forced to conform thereto by suitable pressure. The plate being thus flattened, it is evident that the 10 previously convex surface must receive a substantial compression or shortening in the operation; the extent of such contraction being of course controlled by the curvature of the mold 10 and the thickness of the 15 plate. In this condition the plate is planed down to the quarter or three-sixteenths of an inch thickness required to fit it for the printing cylinder, as indicated by the dotted line 3. It is then laid in the mold 15 face 20 downward, and brought to its final shape in the usual manner; the curvature of this mold being of course of equal radius to that of the printing surface. As the plate is thus bent to its final curvature, its printing 25 surface is elongated to an amount exactly equal to its contraction when flattened from its original curved form.

The secret of making the two opposite distortions exactly equal each other, and 30 thereby bring the printing surface back to its original dimensions, is to have the original curvature of the plate multiplied by its original thickness equal its final curvature multiplied by its final thickness; and as curvature is inversely proportional to radius, the original radius of mold multiplied by the 35 final thickness of plate should equal the final radius of mold multiplied by original thickness of plate. Hence the curvature 40 of the first mold 10 should be much flatter than the final mold 15.

My second method, and the one which I prefer, mainly because of the superior ease with which the electro-shell can be backed 45 up when flat, is as follows: The first step consists in laying the electro-shell face downward upon a flat surface 12', and then pouring the melted alloy backing thereon to the usual half-inch in thickness. This plate 50 when cool is then removed to the cylindrical surface 20, with its face inward, and bent into conformity therewith, and, while there, turned or routed down to the desired quarter or three-sixteenths inch thickness, as indicated by the dotted line 3. This thinned plate is now, bent back to its original flat shape, and applied to the mold 15' face 55 downward, and brought to its final curvature.

60 During the bendings from flat to concave; and from concave to convex, the contraction of the first must be made to exactly equal the elongation of the second; but inasmuch as the final bendings after thinning are from

concave to convex, the cylinder 20 must be 65 much less flat than the original mold 10 in the first method, and above formula cannot now be applied, but the radius of the surface 20 must be very nearly that of the final mold 15', depending upon whether the plate is 70 thinned from one-half to one-fourth or from one-half to three-sixteenths. If the latter, the surface 20 should be flatter than the surface 15'.

Although I have specified this process as 75 applicable to electrotype plates, I do not restrict myself thereto, as the method is equally valuable for other metal-backed printing surfaces. Hence, in the claims, I employ the term "electrotype," in all cases 80 where its signification is not otherwise restricted, to designate any metal-backed printing surface.

The claims herein are specific to the more generic ones in my companion application 85 Serial No. 409,805.

What I claim as my invention and for which I desire Letters Patent is as follows, to wit:—

1. The herein described method of preparing printing surfaces, consisting in giving the backed printing surface two opposite and unequal bendings, and between such bendings so thinning the backing as to cause the second bending to give a reduced distortion to said surface. 90

2. The herein described method of preparing printing surfaces, consisting in first bending an excessively backed printing surface to superficially distort the same, then thinning 100 the backing to gage, and finally bending the same to the desired curvature, whereby superficial distortion of such surface is eliminated.

3. The herein described method of preparing electrotype plates consisting in first backing the electrotype shell with an excessive thickness of fusible metal; then curving the same to compress the printing surface thereof; thinning the backing down to 110 its working thickness; and finally curving the plate to elongate its printing surface and bring it into conformity with the printing cylinder.

4. The herein described method of preparing electrotype plates for use upon cylinder presses, the same consisting in first backing up the electrotype shell upon a flat surface; second, bending the same face down upon a cylindrical surface, and then thinning the 120 backing to its working thickness; and finally bringing the plate to its desired convex curvature. 115

5. The herein described method of preparing electrotype plates for use upon cylinder 125 presses, the same consisting in first placing the electrotype shell upon a flat surface; backing it with lead to an excessive thick-

ness; bending it upon a cylindrical surface of greater radius than the desired printing surface; with its said shell inward; thinning the backing to the desired working thickness; and finally bending the plate to its desired curvature in a proper concave mold.

In testimony that I claim the foregoing

invention, I have hereunto set my hand this 14th day of December, 1906.
